Primary Examiner — Michelle E. Wilson

(74) Attorney, Agent, or Firm — IPS Legal Group, P.A.;
Jocelyn S. Brown, Esq.(57) **CLAIM**

An ornamental design for automatic back washer, as shown.

DESCRIPTION

FIG. 1 is a top perspective view of the present invention.
 FIG. 2 is a bottom perspective view of the present invention.
 FIG. 3 is a front view of the present invention.
 FIG. 4 is a back view of the present invention.
 FIG. 5 is a left view of the present invention.
 FIG. 6 is a right view of the present invention.
 FIG. 7 is a top view of the present invention; and,
 FIG. 8 is a bottom view of the present invention.
